DESIGN FOR A PROGRAM REMINDER

Richard E. Conover, Deer Park, Ohio

Application January 16, 1935, Serial No. 54,871

Term of patent 3½ years

To all whom it may concern:

Be it known that I, Richard E. Conover, a citizen of the United States, residing at Deer Park, in the county of Hamilton and State of Ohio, have invented a new, original, and ornamental Design for a Program Reminder, of which the following is a specification, reference being had to the accompanying drawing, forming part thereof.

Fig. 1 is a face view of the program reminder;

Fig. 2 is a face view of the entire dial of the program reminder; and

Fig. 3 is a vertical central section through the program reminder.

In the drawing the printed matter, including the numerals, days of the week, and title of the device, is merely for illustrative purposes.

I claim:

The ornamental design for a program reminder, substantially as shown and described.

RICHARD E. CONOVER.
